United Shoe Machinery Corporation, Borough
of Flemington, N. J., a corporation of New
Jersey

Original application May 25, 1935, Serial No.
23,462. Divided and this application April 27,
1938, Serial No. 204,598

9 Claims. (Cl. 12—6)

The present invention relates to shoe machines, and is herein shown as embodied in a machine for operating on shoes of the type in which the shoe is supported on a jack and in which the 5 jack and the means for operating on the shoe are moved relatively to transfer the point of operation about the shoe, and to change the relative positions of the shoe and the operating means to cause the shoe to be presented properly 10 to the operating means as the point of operation is transferred about the shoe, all of the relative movements of the shoe and the operating means being produced and controlled by automatically 15 acting mechanisms. While the several features of the present invention are particularly applicable to automatic shoe machines of the type above referred to, certain features of the invention are also capable of use in other types of 20 automatic machines, or in machines in which the shoe is held in position by the operator. It is also to be understood that except as defined in the claims, the several features of the invention are not limited to any particular construction or 25 arrangement of parts.

The present application is a division of application Serial No. 23,462, filed May 25, 1935, to which reference may be had for constructions indicated in the drawings, or herein referred to without being specifically described.

The machine in which the several features of the present invention have been embodied is an automatic machine for sewing the welt and upper to the insole of a welted shoe, and as to the general construction and mode of operation of its 30 various parts is similar to the automatic welt sewing machine disclosed in the applicant's co-pending application Serial No. 655,934, filed February 9, 1933 for Shoe machines.

It is one object of the present invention to 35 provide in a machine for operating on shoes, a novel and improved lasting gripper to engage with and draw the upper firmly into position for a subsequent securing operation.

It is a further object of the present invention to produce an inseam shoe sewing and lasting machine having a simplified and improved construction and mode of operation of its various 40 parts, and particularly of the lasting gripper which operates during a stitch forming cycle to engage the upper in proximity to the needle path and draw the upper into position to be entered by the needle.

With these objects in view, the several features of the present invention consist in the devices, combinations, and arrangement of parts

hereinafter described and claimed which, together with the advantages to be obtained thereby, will be readily understood by one skilled in the art from the following description taken in connection with the accompanying drawings, in which Fig. 1 is a view in front elevation of an automatic welt sewing and lasting machine embodying in a preferred form the several features of the invention; Fig. 2 is an enlarged view in front elevation of a portion of the machine head illustrating particularly the several shoe sewing, guiding and lasting devices of the machine; Fig. 3 is a view in right side elevation of substantially the parts shown in Fig. 2, with the parts shown in stop position; Fig. 4 is an enlarged sectional view illustrating the lasting gripper mechanism, the parts being shown in position in starting the operation on a new shoe, with the lasting gripper in engagement with the lip of the insole and adjacent portion of the shoe upper; Fig. 5 is a fragmentary detail view illustrating a subsequent position of the lasting gripper with the upper drawn firmly into position; Fig. 6 is a detail plan view of the lasting gripper mechanism; and Fig. 7 is a detail view in front elevation of substantially the parts shown in Fig. 6.

The welt shoe sewing machine for sewing the welt to the upper and insole of a shoe while supported on a last herein disclosed as embodying in a preferred form the several features of the present invention, comprises a sewing head generally indicated at 50 within which the sewing and side lasting instrumentalities are housed, a shoe supporting jack comprising a toe support 52 and a heel support 54 pivotally secured thereto, a supporting base 56 within which is housed the supporting and actuating mechanisms for imparting the required feeding, turning and tipping movements to the jack, and a driving and stopping unit for the machine which is housed in a casing 58 on the base adjacent to the sewing head 50.

As has been stated, the general construction and mode of operation of the various parts of the illustrated machine are similar to the corresponding parts of the automatic welt sewing machine disclosed in applicant's pending application Serial No. 655,934. The machine is completely automatic in operation, the shoe being supported on the jack during the sewing operation, and tipping and rotating movements being imparted to the jack in timed relation to the feed of the shoe so as to maintain the shoe at all times in the proper position with relation to the sewing instrumentalities.

As in the machine of the application above re-

ferred to, the devices of the present machine for operating upon a shoe comprise a curved hooked needle 60, a looper 62, a thread finger 64, a thread holder or gripper 66, a channel guide 68, and a welt guide 70. In addition to these devices the present machine also is provided with a side lasting gripper comprising jaws indicated respectively at 72 and 74. Cooperating movements are imparted to these devices for operating 10 on the shoe from a sewing cam shaft 76 which is mounted to rotate on a horizontal axis in bearings in the sewing head 50, and is provided at one end with a spiral gear 78 arranged to mesh with a corresponding spiral gear 80 which is formed 15 integrally with a clutch sleeve 82 loosely mounted to turn on a vertical drive shaft 84 of the machine. The shaft 84 is continuously driven through reduction gearing from an electric motor mounted in the upper end of the casing 58.

20 The control mechanism for imparting positioning and feeding movements to the jack are arranged to impart a continuous feeding movement to the shoe past the stitch forming devices. To assist in the feeding of the work, the needle is 25 mounted to reciprocate with the work in the line of feed. With the present construction, the needle 60 is mounted on a support or frame 86 which extends rearwardly of the machine, and is sleeved to turn on a vertical pivot shaft 88. A rearwardly 30 extending arm 90 formed on the hub of the support 86 carries a cam roll 92 which is arranged to engage in a peripheral cam groove in the cam disk 94 on the sewing shaft 76, so that a reciprocatory movement is imparted to the support and 35 the needle mounted thereon in the line of feed in timed relation to the sewing cycle.

The machine herein disclosed is provided with a novel and improved side lasting gripper which acts along the sides of the shoe as in the applicant's pending application above referred to, to pull in and position the side portions of the upper with relation to the welt and insole in advance of the sewing operation. The operation of the gripper is automatically controlled as the sewing 40 operation progresses around the shoe to cause the gripper to operate intermittently and progressively along the side of the shoe in time with the stitch forming devices, to cease operating as the sewing proceeds about the toe which has preferably been previously molded, and finally to resume 45 operation again as the sewing is continued along the other side of the shoe. In accordance with certain features of the present invention, this lasting gripper is constructed and arranged to insure the engagement of the gripper with a comparatively short or closely trimmed upper, and has a novel and improved operation with relation 50 to the sewing and feeding devices of the machine to permit a more compact and efficient arrangement of the several cooperating mechanisms for lasting the upper and for stitching the 55 welt to the assembled insole and upper of the shoe.

As best shown in Figs. 2 and 4, the gripper is 60 located adjacent to and immediately in advance of the needle in the line of feed, being supported against movement in the line of feed upon a stationary support. The jaw 72 comprising one of the cooperating members of the gripper, is rigidly 65 formed on the offset lower end of a slide 180 mounted for vertical movements in a guideway 182 formed on the supporting bracket for the channel guide 68. The cooperating jaw 74 of the gripper is pivotally mounted on a stud 184 on the offset portion of the slide 180 to move vertically with

the jaw 72 toward and away from the work as a single unit.

The gripper unit mounted in this manner for movements only in a plane normal to the line of feed has the advantage that it can be located in close proximity to the point of operation of the needle about which the shoe is turned as the stitching operation progresses around the shoe sole without interference with other parts of the machine, and more particularly the welt guide. 10 It has been found that the continued feed of the shoe during the relatively brief updraw movement of the gripper unit to pull in the upper serves to assist in positioning the upper tightly and accurately in position for the subsequent formation of a new stitch without at the same time seriously affecting the fit of the upper over the last. As has been stated, the feeding movement which is imparted to the work is continuous. As a consequence the movement of the work in the 20 line of feed, while the lasting gripper is grasping the upper, is comparatively small, being only a portion of the entire movement during a stitch forming cycle, and is not sufficient to wrinkle the upper or interfere with the proper operation of 25 the gripper, although no movement in the line of feed is imparted to the gripper during its upper drawing movement. Due to the continuous feeding movement of the work also, and particularly to the fact that the feeding movement is produced 30 by the movement of the jack, a uniform spacing of the stitches is secured and irregularities or uncertainty in the operation of the work feeding and stitch forming devices by reason of the upper lasting operation is avoided.

In order to insure the engagement and drawing-in of a short or closely trimmed upper, a feature of the present invention consists in the provision of a gripper unit of novel and improved construction having a mode of operation which 40 enables the gripper to engage with and exert a drawing-in action on the upper at a point much closer to the shoe sole than has heretofore been considered possible without interference with the associated parts of the shoe and last. To this 45 end the jaw 72 of the gripper is constructed and arranged to move downwardly against the shoe sole inside of the channel lip, and is provided with a smooth gripping surface adapted for gripping engagement against the inside face of the upturned channel lip of the insole at the base thereof. The cooperating jaw 74 is provided with a roughened or corrugated gripping surface which 50 is arranged to be brought into gripping engagement with the outer surface of the upper overlying the edge of the shoe inner sole and channel lip. In the operation of this mechanism, the jaws are moved downwardly in open position, and are then permitted to draw together under the pressure of their spring, so that the inner jaw 55 72 is yieldingly pressed against the channel lip, and the cooperating corrugated gripping surface of the outer jaw engages firmly against the outer portion of the upper which is supported during the subsequent up-draw movement of the gripper, 60 first against the edge of the inner sole and channel lip, and finally against the smooth surface of the gripper jaw 72 as the jaw 72 rides out of engagement with the channel lip during the continued up-draw movement of the gripper unit. 65 Vertical movements are imparted to the slide 180 to move the gripper toward and away from the work by means of a cam lever 188 supported on a pivot shaft 190 and a lever arm 192 connected to the cam lever 188 as hereinafter de- 70 75

scribed, which lever arm is provided at its forward end with a transverse slot 194 to receive a pivot block 196 on the upper end of the slide 188. The cam lever 188 carries a cam roll 198 which engages in a groove 200 formed in one face of the cam disk 94 to impart a single reciprocatory movement to the cam lever for each revolution of the cam shaft 76. A broken connection is provided between the cam lever 188 and actuating lever 192, so that a yielding downward movement and a positive updraw is imparted to the gripper during each cycle of operations of the machine. The upward movement of the actuating lever 192 is caused by the engagement of an abutment 202 on the sleeve hub of the lever 192 with a corresponding abutment 204 on the sleeve hub of the cam lever 188. The actuating lever 192 is moved downwardly as the roll 198 rides onto the high portion of its cam groove 200 under the influence of a compression spring 206 seated in recesses 208 and 210 in the sleeve hubs of the actuating lever 192 and cam lever 188 respectively.

The jaw 74 is moved positively into open position or yieldingly into closed or gripping relationship to the jaw 72 through connections which include a cam lever 212 loosely mounted to turn on the shaft 198, and provided at its rear end with a roll 214 arranged to engage in a cam groove 216 in one face of the cam disk 94. At its forward end the cam lever 212 is provided with a pivot block 218 journaled to receive the upper end of a link 220 which is pivotally connected at its lower end to a laterally extending portion of the gripper jaw 74. Locking nuts 222, screw-threaded to the link 220, are arranged to engage with the upper side of the pivot block 218, so that a positive upward movement is imparted to the link 220 by the operation of the cam lever 212 to spread or open the jaws of the gripper. A compression spring 224 surrounding the link 220 between the under side of the pivot block 218 and locking nuts 226 on the line 220, acts to impart a yielding downward movement to the link 220 and the cam lever 212, so that a yielding gripping action of the jaws of the gripper is obtained.

To enable the gripper to be thrown out of action, a detent lever 227 is provided pivoted at 228 on the machine frame, and normally held by a spring 229 in engagement with the abutment 202 on the sleeve hub of the lever 192 to maintain the gripper in raised inoperative position against the pressure of the spring 206. During the operation of the lasting gripper the detent lever 227 is held out of engagement with the abutment 202 by the engagement of a vertically movable control rod 230 with the tail of the detent lever 227.

In the performance of the sewing and side lasting operations around the shoe sole, the side lasting grippers commence operating when the machine is thrown into operation from the starting position at the shank, are thrown out during the sewing operation around the toe, and are again rendered operative as the stitching operation returns along the other side of the shoe to the shank. The operation of the control rod 230 to move the gripper into and out of operation is controlled automatically through a set of operating connections and a cam on the pattern cam shaft of the machine not here illustrated, inasmuch as these parts are identical with those fully described and illustrated in the applicant's

co-pending application Serial No. 655,934, above referred to.

The invention having been described, what is claimed is:

1. In a machine for operating upon shoes, the combination with guiding devices for the assembled insole and upper of a shoe supported on a last, of means for attaching the upper to the insole, a lasting gripper comprising cooperating jaws, one of said jaws being arranged to slide transversely of the rib of the insole while in engagement therewith at the limit of the downward movement of the gripper, and the other of said jaws being arranged for gripping engagement with the adjacent portion of the shoe upper and means for actuating the jaws to grip the upper and for moving both jaws away from the work to tension the upper.

2. In a machine for operating upon shoes, the combination with guiding devices for the assembled insole and upper of a shoe supported on a last, of means for attaching the upper to the insole, a lasting gripper comprising cooperating jaws, one of said jaws having a smooth engaging surface arranged to slide transversely of the rib of the insole while in engagement therewith at the limit of the downward movement of the gripper, and the other of said jaws having a roughened engaging surface arranged for gripping engagement with the adjacent outer surface of the shoe upper and means, for actuating the jaws to grip the upper and for moving both jaws away from the work to tension the upper.

3. In a machine for operating upon shoes, the combination with guiding devices for the assembled insole and upper of a shoe supported on a last, of means for attaching the upper to the insole, a lasting gripper comprising cooperating yieldingly actuated jaws, one of said jaws being arranged to slide transversely of the rib of the insole while in engagement therewith at the limit of the downward movement of the gripper, and the other of said jaws being arranged for gripping engagement with the adjacent portion of the shoe upper, and means for imparting a yielding gripping action to said jaws and for moving both jaws away from the work to tension the upper.

4. In a machine for operating upon shoes, the combination with guiding devices for the assembled insole and upper of a shoe supported on a last, of means for attaching the upper to the insole, a lasting gripper comprising cooperating yieldingly actuated jaws, one of said jaws having a smooth engaging surface arranged to slide transversely of the rib of the insole while in engagement therewith at the limit of the downward movement of the gripper, and the other of said jaws having a roughened engaging surface arranged for gripping engagement with the adjacent outer surface of the shoe upper, and means for imparting a yielding gripping action to said jaws and for moving both jaws away from the work to tension the upper.

5. In a machine for operating upon shoes, the combination of means for attaching the upper to the insole, a shoe supporting jack, means for moving the jack and shoe supported thereon relatively to the attaching means to transfer the point of operation about the shoe, a stationary channel guide, and a lasting gripper mounted on said channel guide to operate transversely of the line of feed adjacent the point of operation of the attaching means to engage with and position

- successive portions of the upper for the operation of said attaching means.
6. A sewing and lasting machine for attaching the upper and insole of a shoe assembled on a last having, in combination, stitch forming and work feeding devices including means for imparting a continuous feeding movement to the work and a lasting gripper supported against movement in the line of feed and arranged to operate transversely of the line of feed adjacent the point of operation of the stitch forming devices to engage with and position successive portions of the upper for the operation of said stitch forming devices.
7. A sewing and lasting machine for attaching the upper and insole of a shoe assembled on a last having, in combination, stitch forming and work feeding devices including a shoe supporting jack, a lasting gripper supported against movement in the line of feed and arranged to operate transversely of the line of feed adjacent the point of operation of the stitch forming devices to engage with and position successive portions of the upper for the operation of said stitch forming devices, and means for actuating the jack to feed the work during the engagement of the lasting gripper with the upper.
8. A sewing and lasting machine for attaching the upper and insole of a shoe assembled on a last having, in combination, stitch forming and work feeding devices, means including a shoe supporting jack for imparting a continuous feeding movement to the work, and a lasting gripper supported against movement in the line of feed and arranged to operate transversely of the line of feed adjacent the point of operation of the stitch forming devices to engage with and position successive portions of the upper for the operation of said stitch forming devices.
9. A sewing and lasting machine for attaching the upper and insole of a shoe assembled on a last having, in combination, stitch forming and work feeding devices, a lasting gripper supported against movement in the line of feed and arranged to operate transversely of the line of feed adjacent the point of operation of the stitch forming devices, and means for actuating the lasting gripper to engage with and position successive portions of the upper during the feeding movement of the work for the operation of said stitch forming devices.

ALFRED R. MORRILL. 25
